UNITED STATES PATENT OFFICE

ALFRED N. GOLDSMITH, OF NEW YORK, N. Y., ASSIGNOR TO RADIO CORPORATION OF AMERICA, A CORPORATION OF DELAWARE

ULTRA-SHORT WAVE REPEATING SYSTEM

Application filed April 30, 1932. Serial No. 608,359.

This invention relates to a method of, and apparatus for relaying radio signals.

It is well known that electromagnetic waves at the lower wave lengths below 10 meters have characteristics which are quasi-optical in nature; that is, they have a very definite limited range of transmission which is comparable with the optical range or visible distance. It is also known that the inter-position of objects or the presence of reflecting objects near or in the path of transmission affects, to an extent at least, the ability of a station to receive the radiated energy, and that the condition of the local topography is an important element of consideration in ultra-short wave communication.

One arrangement heretofore suggested for transmitting ultra-short wave signals between points separated by a distance greater than the optical range has been to locate relay or repeater stations at frequent intervals along the line of transmission for amplifying and reradiating the signals. It has been proposed to provide these relay stations with two directive antennae, one for receiving the signal from the station nearest the transmitting end and the other for reradiating the signal to the next adjacent station nearest the receiving terminal. Such an arrangement is described in my copending application Serial No. 594,238, filed February 20, 1932, and in a copending application Serial No. 611,769 filed May 17, 1932, by F. H. Kroger.

The foregoing arrangements referred to are not limited in scope to the transmission of any one type of radio signal, but may be utilized to transmit telegraph signals, television, telephony or other suitable forms of modulation. When used for the transmission of television, telephone, facsimile, or other broadcasting services for the syndication of programs between points widely separated, the repeater stations of these systems are useful not only as relay stations, but, it has been found, may (with suitable arrangements) also be used as local broadcasting stations in rural districts where the economics of the situation do not otherwise warrant the erection of television or telephone broad-

casting stations. For example, a radio transmission line may be used to send programs, such as television, telephone or both, from New York to Chicago. Such line would pass, in part, through rural areas. Due to the fact that the repeater stations are provided with highly directional antennae, for reasons of efficiency in operation, these areas would otherwise be beyond the range of the ultra-short wave broadcasting stations at the terminals of the line, due to the quasi-optical nature of the electromagnetic waves used, and would not be effectively served by the intervening highly directional relay stations. According to the present invention, it is proposed to provide at one or more repeater stations on the transmission line a non-directional (broadcasting) transmitter, in addition to the directional type. Accordingly, whatever programs are passed over the line are spread out at right angles to the transmission line as well as in the direct line of transmission and thus give service to a desired area.

More particularly, the present invention comprises a radio communication system having a plurality of repeater stations located between the terminal transmitting and receiving stations. Each of these repeaters may comprise a plurality of directional antennae which are individually positioned or arranged to be effective in different directions towards the next adjacent repeater station. At any desired one or more of the repeater stations there is provided a local broadcasting transmitter station which is arranged to serve rural areas with broadcasting service effectively. The wave lengths of the relay stations and of the associated broadcasting stations are selected with due regard to the corresponding service to be rendered. The message signals for the local broadcasting stations may be obtained, in any suitable manner, from the radio transmission line signals. One way of effecting this is to demodulate the signals passing along the radio transmission line and use them to control the broadcasting transmitter located at the repeater station. The frequency of trans-

mission from this broadcasting transmitter may be of any desired value, either the same or different from that used by the relaying stations, as previously stated.

5 A better understanding of the invention may be had by referring to the following description, accompanied by a single drawing, wherein there is shown, diagrammatically, a radio communication system embodying the 10 principles of the present invention.

Referring to the drawing, there are shown an "originating" station A and a "terminal" station C, between which it is desired to transmit signals. As indicated in the drawing by the direction of the arrows, station A is arranged to transmit signals and station C to receive signals. Intermediate A and C are a plurality of repeater or relay stations R, R' and R''. These repeaters are 15 each provided with two directional antennas, one of which is adapted to receive signals and is operative in the direction of the next adjacent transmitting station and the other of which is adapted to transmit signals 20 in the direction of the next adjacent receiving station. Since the transmission range of the ultra-short waves depends upon the air line or visible distance, a factor proportional to the height above the earth's surface, 25 it is proposed to locate all stations at points having as great heights as possible, such as mountains, tall buildings, radio masts, etc.

The directional antennae may be of any suitable type and may or may not use a reflector. A transmitting antenna such as developed at present consists of a copper sheet about 6'x6' on which are mounted insulators for supporting a system of half wave elements parallel to and one-quarter wave 40 length away from the copper sheet. The sheet acts as a reflector. On a two-way circuit, i. e., where transmission may be effected in two directions and wherein automatically reversing signal repeaters are not provided, these antennas would be mounted back to back at the top of the repeater station tower and the receiving antennas would be mounted alongside the transmitting antennae.

50 Transmitting station A is shown as functioning on a frequency of 60,000 k. c. It is to be understood, of course, that any other suitable frequency may be utilized. This signal is received at repeater R on the directive antenna r, amplified, converted to a new frequency of 59,000 k. c. by beating with a local oscillator of 1,000 k. c. and is then re-radiated on directive antenna t at 59,000 k. c. At repeater R' the 59,000 k. c. signal is received on antenna r and is converted to a new frequency of 58,000 k. c., amplified and re-radiated at 58,000 k. c. on transmitting antenna t. Likewise, at relay point R'' the 58,000 k. c. is received, converted to 60,000 65 k. c., amplified and re-radiated. The 60,000

k. c. is the same frequency originally transmitted at transmitter A. These same three frequencies may now be used over again in the same sequence as many times as may be desired. Since the range of these ultra-short 70 wave transmitters is limited to points slightly beyond the distance between the relay points it is impossible for the radiation of the 60,000 k. c. from station C to reach back to repeater R which is capable of receiving 75 60,000 k. c. Thus, by the use of these three frequencies, all possibility of instability is entirely eliminated. Although, the use of three frequencies is preferable in this arrangement and is thought to be the most 80 practical from an operating standpoint, it is to be understood that, if desired, a similar system utilizing only two frequencies with suitable directive antennas may be employed. Or any other suitable system of relay stations may be used such as one utilizing only 85 a single frequency of the type described in my copending application, Serial No. 594,-238, referred to above.

At repeater station R' there is shown a local broadcasting station B, the input of which is obtained from the radio transmission line signals. One method of connecting the broadcasting station to the radio transmission line would be to demodulate the signals passing along the line and to use the resulting energy to control the broadcasting transmitter B located at the repeater station R'. Alternatively, if desired, the transmission line signal may be heterodyned with 90 some suitable frequency and the resulting energy used to obtain a new frequency signal which, with radio frequency power amplification, would permit the broadcasting transmitter to operate. In the type of system indicated in the drawing the frequency of transmission from the broadcasting transmitter would, of course, be of any desired 95 value other than the frequency used on the radio transmission line in order to prevent 100 undesirable feed-back effects. However, if the present invention is used with a system of the type described in my copending application, Serial No. 594,238, supra, the frequency 105 may be the same as that used by the relaying 110 station. An advantage of the latter arrangement is that should the relaying station associated with the local broadcasting transmitter fail to transmit the transmission line signal the broadcasting signal might be utilized by the next adjacent receiving repeater 115 station.

Transmitter B is arranged to be an automatically operating broadcasting transmitter (as distinguished from a directional) and 120 may be connected to any one or more of the repeater stations to serve rural areas with broadcasting service effectively. Of course, the power of the broadcasting transmitter 125 may be adjusted independently to whatever 130

value it is desired to give adequate service.

It is to be distinctly understood that this invention is not limited in application to the precise arrangement shown since it is apparent that it is susceptible of being modified to meet the different conditions encountered in its use and it is, therefore, aimed to cover by the appended claims all modifications within the spirit and scope of the present invention.

10 I claim:

1. An ultra-short wave radio communication system of the type comprising a transmitting station, a remote receiving station, and a plurality of intermediate repeater stations between said transmitting and receiving stations, each of said repeater stations having a directive receiving antenna positioned to receive signal waves from its next adjacent station located in the direction of the transmitting station and a directive transmitting antenna positioned to transmit signal waves towards its next adjacent station located in the approximate direction of the receiver, characterized in this, that to at least one of said intermediate receiving stations there is connected signal transmitting equipment associated with a non-directional

antenna for broadcasting purposes, said transmitting equipment being adapted to receive signals being relayed over said system from station to station.

2. An ultra-short wave radio communication system of the type comprising a transmitting station, a remote receiving station, and a plurality of intermediate repeater stations between said transmitting and receiving stations, each of said repeater stations having a directive receiving antenna positioned to receive signal waves from its next adjacent station located in the direction of the transmitting station and a directive transmitting antenna positioned to transmit signal waves toward its next adjacent station located in the approximate direction of the receiver, characterized in this, that to at least one of said intermediate repeater stations there is connected signal transmitting equipment associated with a non-directional antenna for broadcasting purposes, said transmitting equipment being adapted to receive signals of one of the frequencies being relayed over said system and to broadcast signals on a different frequency.
